UNITED STATES PATENT OFFICE.

ERWIN C. COOPER, OF DETROIT, MICHIGAN, ASSIGNOR TO PACKARD MOTOR CAR COMPANY, OF DETROIT, MICHIGAN, A CORPORATION OF MICHIGAN.

MOTOR-VEHICLE.

1,358,935.

Specification of Letters Patent. Patented Nov. 16, 1920.

Application filed February 6, 1913. Serial No. 746,578.

To all whom it may concern:

Be it known that I, ERWIN C. COOPER, a citizen of the United States, and resident of Detroit, Wayne county, State of Michigan, have invented certain new and useful Improvements in Motor-Vehicles, of which the following is a specification.

This invention relates to motor vehicles. It particularly refers to vehicles using hydrocarbon motors, and one of the objects of the invention is to provide a motor of this type with a starting motor that may be temporarily connected to the vehicle motor by means that are easily operated by the driver. 15 One embodiment of the invention is shown and described herein, and it comprises a hydrocarbon motor and a starting motor, which may be either an electric motor or an air motor or other suitable similar motor, 20 which is connected to the crank shaft of the vehicle through a train of reducing gears.

Another object of the invention is to provide a train of gearing between the starting motor and the vehicle motor in combination 25 with a suitable clutch mechanism for connecting the train of gears operatively to the vehicle motor crank shaft.

Another object of the invention is to provide a novel form of clutch mechanism between the vehicle motor crank shaft and the hand starting crank and the starting shaft 30 for the starting motor.

Another object of the invention is to provide a single device for operating the starting clutch mechanism and for throwing the switch to close the circuit of the starting motor, or, in case the starting motor is an air motor, to operate the valve thereof.

With a view to attaining these and other 40 objects, which will become apparent to those skilled in the art, the invention consists in the features of construction and arrangement of parts hereinafter more fully described and specified in the claims.

45 Referring to the drawings which form a part of this specification,

Figure 1 is a plan view and part horizontal section of the front end of a motor, together with contiguous parts of the vehicle 50 frame;

Fig. 2 is an elevation of the front end of the motor shown in Fig. 1, with part of one of the covers broken away; and

Fig. 3 is a detail view of the starting 55 lever.

In the drawings, one of the side bars of the vehicle frame is indicated at 10, and two of the cross bars at 11. The motor is suitably suspended from this frame and comprises a crank case 12 in which the crank 60 shaft 13 is mounted in suitable bearings, not shown.

In Fig. 1, one of the cam shafts 14 is shown as mounted in a bearing 15 in the crank case, and an auxiliary shaft 16 is 65 mounted in bearings 17. The rear end of the shaft 16 is provided with a universal joint 18 and a gear 19, by which any suitable motor mechanism, such as a magneto or generator, may be driven.

The forward end of the shaft 16 is provided with a pulley 20 for driving the motor fan.

Upon the front end of the crank shaft 13 is keyed a gear 21 which meshes with a gear 75 22 on the cam shaft 14, the latter gear driving a gear 23 secured to the shaft 16. Thus a train of gears is provided for operating the motor cam shaft and other parts of the motor.

The front end of the crank case is closed by a cover 24, shown in section in Fig. 1 and in elevation in Fig. 2, thereby forming a casing for the train of gears 21, 22 and 23. It will be understood that there are gears 85 similar to gears 22 and 23 extending on the other side of the crank shaft 13, all of which gears are housed within this gear casing.

It is well known that hydrocarbon motors must be "cranked", that is, rotated several times in order to charge the cylinders and start the motor on its operating cycle. This may either be done by a hand operated mechanism or by an auxiliary motor or starting motor, such as a small electric or 90 air motor. The present invention involves the use of a starting motor and a train of gearing connecting such motor to the vehicle motor, together with a suitable clutch for connecting the gearing to the vehicle motor 100 crank shaft. As shown in the drawings, the starting motor consists of an electric motor 25, the windings of which may be energized by a battery 26 through conductors 27 and a switch 28. The armature shaft of this 105 starting motor 25 is connected through suitable universal joints 29 to a gear 30, which is shown as being on the outer side of the cover 24. It will be seen in Fig. 2 that this motor 25 is suspended from the crank case 110

or vehicle frame somewhat below the train of gears 21, 22 and 23, hereinabove described, so that it will not interfere in any way with the motor parts driven by said 5 gears.

A stub-shaft 31 is secured in a boss 32 in the cover 24, and upon this shaft is mounted a large gear 33, which meshes with gear 30, and a small gear 34, which meshes with a 10 large gear 35, secured on a shaft 36 mounted in axial alinement with the crank shaft 13.

The gears 30, 33, 34 and 35 thus form a train of gears which considerably reduces the speed of the shaft 36 relative to the armature shaft, and it will be noted that this 15 train of gears is mounted parallel relative to the train of gears 21, 22 and 23 but outside of the cover 24, being in fact supported upon said cover.

20 This train of gears is also provided with a cover 37 which is detachably secured to the cover 24, as by bolts 38, shown particularly in Fig. 2.

The shaft 36 is mounted in the covers 24 25 and 37 in bearings 39, and is adapted to slide lengthwise in said bearings, and in this connection it will be noted that the width of the gear 34 is slightly greater than that of the gear 35, to permit of the sliding of the latter gear without decreasing the width of teeth in mesh.

The inner end of the shaft 36 is provided with clutching jaws 40, which are adapted to coöperate with clutching jaws 41 on a clutch 35 piece 42, which is likewise keyed to the front end of the crank shaft 13 and held thereon, together with the gear 21, by means of a nut 43. The shaft 36 is yieldingly held in disengaged position by a leaf spring 44 secured to the front face of the cover 24, as shown in Figs. 1 and 2.

Concentrically arranged and, in fact, mounted within the interior of the shaft 36 is a second starting shaft 45, which is also 45 provided with clutching jaws 46 which are likewise in the crank case and which coöperate with the jaws 41 on the clutching piece 42, the latter jaws being sufficiently long radially to engage with the jaws of both shafts 36 and 45. A spring 47, which has a bearing against the reduced end 48 of the crank shaft 13 and which is housed within the interior of the shaft 45, tends to yieldingly hold the starting shaft 45 in disengaged position. A stop 49 sliding in an annular slot 50 limits the travel of the shaft 45, as will be clearly seen in Fig. 1.

The starting shaft 45 is connected with the starting crank 51, which is the usual hand crank by which the motor may be "turned over" by hand.

It will be understood that the spring 44 holds the starting shaft 36 yieldingly in disengaged position, but it is shown in Fig. 65 1 in engaged position, having been moved

into that position by means of a lever 52 pivoted in lugs 53 on the cover 37 and having a roller 54 engaging the forward projecting end of the shaft 36. The other end of the lever 52 is connected by a link 55 with 70 a bell crank lever 56 which is operated by a starting pedal 57, the lever 56 being pivoted in the bracket 58 on one of the cross members 11 of the vehicle frame. The lever 56 is also connected to a rock shaft 59, which 75 has an arm 60 connected by a rod 61 to the bridging piece 62 of the switch 28, this bridging piece connecting the terminals 63 to close the circuit of the battery 26, which thereby sets the motor 25 in operation. 80

The connection of the link 55 with the downwardly extending arm of the bell crank lever 56 is shown particularly in Figs. 1 and 3. It will be seen that these parts have a pin and slot connection and that the pin 64 85 is yieldingly held at one end of the slot by a spring 65 and a plunger 66. Thus, when the starting pedal 57 is depressed, the connecting link 55 is moved forwardly and the lever 52 is rocked to move the starting shaft 90 36 into engaging position with the teeth 41 of the crank shaft. If the teeth happen to be so positioned relatively that they will not readily mesh, the starting pedal 57 may be further depressed, thus compressing the 95 spring 65 in the connection of the link 55, which at the same time rocks the shaft 59 and moves the bridging piece 62 into contact with the terminals 63, thereby closing the circuit of the battery 26 and the motor 25. 100 This starts the operation of the train of gears 30, 33, 34 and 35, and consequently rotates the shaft 36 so that the clutching jaws 41 and then take up the crank shaft and 105 rotate it. By this arrangement, it is insured that the starting shaft 36 will be in clutching position before the switch is closed for starting the electric motor.

A specific embodiment of the invention 110 has been described in detail and will be specifically claimed, but it is understood that the invention is not limited to the exact details of construction shown, as it will be apparent that changes may be made without departing from the spirit and scope of the invention.

Having thus described my invention, what I claim and desire to secure by Letters Patent is:

1. In a hydrocarbon motor, the combination with the crank casing having a gear casing formed at one end thereof, and a train of gears in said casing for driving the operative parts of the motor, of a starting motor, 125 a train of gears therefrom to the motor crank shaft mounted on the outside wall of said gear casing, and a cover for said latter train of gears.

2. In a hydrocarbon motor, the combina- 130

- tion with the crank shaft, of a starting shaft alined therewith, a clutch mechanism ar-
ranged to connect the starting shaft with the
crank shaft, a second starting shaft arranged
5 to be connected with the crank shaft by
clutch mechanism having a clutch element in
common with the first mentioned clutch
mechanism, and means for operating said
clutch mechanism. 70
- 10 3. In a hydrocarbon motor, the combina-
tion with the crank case and the crank shaft
mounted therein, of a starting shaft mount-
ed in bearings in the crank case and adapted
to engage the crank shaft for starting, a
15 second starting shaft mounted within the
first starting shaft and adapted to independ-
ently engage the crank shaft for starting,
and means for operating said starting shafts
independently. 75
- 20 4. In a hydrocarbon motor, the combina-
tion with the crank case and the crank shaft
mounted therein, of a starting shaft mount-
ed in bearings in the crank case and adapted
to engage the crank shaft for starting, a
25 second starting shaft mounted within the
first starting shaft and adapted to independ-
ently engage the crank shaft for starting,
and means for operating said starting shafts
independently. 80
- 30 5. In a hydrocarbon motor, the combina-
tion with the crank case and the crank shaft
mounted therein, of a starting shaft mount-
ed in bearings in the crank case and adapted
to engage the crank shaft for starting, a
35 second starting shaft mounted within the
first starting shaft and adapted to independ-
ently engage the crank shaft for starting a
spring between the crank case and one of
said starting shafts, a spring between the
40 crank shaft and the other said starting shaft,
said springs adapted to retain said starting
shafts yieldingly in disengaged position, and
independent manually operated devices for
moving said starting shafts into engagement
45 with said crank shaft. 85
- 50 6. In a hydrocarbon motor, the combina-
tion with the crank shaft having a clutch
member thereon, of two concentrically ar-
ranged starting shafts having clutch mem-
bers adapted to coöperate with said clutch
member, and means for independently mov-
ing either of said starting shafts to bring
their respective clutch members into engage-
ment with the first said clutch member. 90
- 55 7. In a hydrocarbon motor, the combina-
tion with the crank shaft having a clutch
member thereon, of two concentrically ar-
ranged starting shafts having clutch mem-
bers adapted to coöperate with said clutch
60 member, and a gear on one and a starting
handle on the other of said starting shafts
for operating them respectively. 95
- 65 8. In a hydrocarbon motor, the combina-
tion with the crank case and the crank shaft
therein, of a starting motor, a train of gears
130 having a gear connected to said starting
motor and a gear in axial alinement with
said crank shaft, and a sliding clutch con-
nected to said latter gear and adapted to
connect with said crank shaft. 100
9. In a hydrocarbon motor, the combina-
tion with the crank case and the crank shaft
therein, of a starting motor, a train of gears
having a gear connected to said starting
motor and a gear in axial alinement with
135 said crank shaft, a sliding clutch connected
to said latter gear and adapted to connect
with said crank shaft, and a hand operated
starting crank extending through said clutch
and adapted to independently connect with
140 said crank shaft. 105
10. In a hydrocarbon motor, the combina-
tion with the crank case and the crank shaft
therein, of a starting motor, a train of gears
having a gear connected to said starting
motor, a starting shaft connected to another
145 of said train of gears, a clutch on said shaft
for engagement with the crank shaft, and
a hand operated starting shaft slidably
mounted in the first said starting shaft and
adapted to independently engage said crank
150 shaft. 110
11. In a motor vehicle, the combination
with the hydrocarbon motor thereof, of a
starting motor having a starting switch, a
train of gears from the starting motor to
the vehicle motor crank shaft, a clutch for
connecting said train of gears to said crank
shaft, and a single operating device yield-
ingly connected to operate said clutch and
rigidly connected to operate said switch. 115
12. In a motor vehicle, the combination
with the hydrocarbon motor thereof, of a
starting motor having a starting switch, a
train of gears from the starting motor to
the vehicle motor crank shaft, a clutch for
connecting said train of gears to said crank
shaft, an operating lever, a connection
from said lever to said clutch to move
the same into operative engagement with
160 said crank shaft, said connection includ-
ing a yielding element, and a rigid con-
nection from said operating lever to said
switch to close the latter when the said
clutch is fully engaged or upon the contrac-
tion of said yielding element. 110
13. In combination, an engine shaft, a
slidably mounted starting shaft in aline-
ment therewith, adapted for engagement by
manually operable means, a clutch member
165 on said engine shaft, a gear wheel fixed on
said starting shaft and adapted to engage
said clutch member, a motor, and reduction
gearing operatively connecting said motor
to said gear wheel. 120
14. In combination, a crank case, an en-
gine shaft mounted therein, a clutch member
fixed thereon, a clutch member slidably
mounted in bearings in the crank case adapt-
ed to co-act with said first named clutch 125

member, means for normally retaining the
slidable clutch member in an inoperative
position, a motor, and gearing for opera-
tively connecting said motor to said slidable
5 clutch member.

15. In combination, a crank case, an en-
gine shaft mounted therein, a starting shaft
slidably and rotatably mounted in said case
and in alinement with said engine shaft,
10 a clutch member on said engine shaft,
a clutch member on said starting shaft
adapted to coöperate with the first named
clutch member, means for yieldingly sepa-
rating said clutch members, and a motor op-
15 eratively connected to said starting shaft.

16. In combination, a crank case, an en-
gine shaft mounted therein, a slidably
mounted starting shaft mounted in bearings
in said case and in alinement with said en-
gine shaft and adapted to engage the same, 20
means for yieldingly retaining said starting
shaft in a disengaged position, means for
reciprocating said starting shaft, and a motor
operatively connected to said starting shaft.

In testimony whereof I affix my signature 25
in the presence of two witnesses.
